CARL HARTMANN, OF LANCASTER, NEW YORK, ASSIGNOR TO GOULD COUPLER COMPANY, A CORPORATION OF NEW YORK.

IGNITION SYSTEM.

1,151,946.

Specification of Letters Patent. Patented Aug. 31, 1915.

Application filed June 11, 1913. Serial No. 773,010.

To all whom it may concern:

Be it known that I, CARL HARTMANN, a subject of the Emperor of Germany, and a resident of Lancaster, county of Erie, and State of New York, have invented certain new and useful Improvements in Ignition Systems, of which the following is a specification.

My invention relates to ignition systems for gas engines and the like, and more particularly to a system in which both a source of direct current, as a battery, and its circuit, and a source of alternating current and its circuit, are embodied and adapted to be used for causing ignition in sparking devices.

The main object of my invention is to provide a new arrangement of interrupter connections, whereby the system is generally more satisfactory and reliable.

Further objects, features and advantages will more clearly appear from the detailed description given below taken in connection with the accompanying drawing, which illustrates diagrammatically a system embodying my improvements in one form.

Referring to the drawing, 1—1, &c., represent suitable sparking or ignition devices of an engine or the like. Each of these is connected by wires 2—2, &c., to contact plates 3—3, &c., of a distributor having a rotating member 4 connected to wire 5, which rotating member is adapted to connect the sparking devices consecutively with one of the sources of current.

6 represents a storage battery having one terminal connected to ground at 7 by means of wire 8, and the other terminal connected to one contact 9 of a switch 10, by means of a wire 11.

12 represents an alternating current dynamo or magneto or other source of alternating current having one terminal connected to ground by means of wire 13, and the other terminal by means of wire 14 being connected to contact 15 of the switch 10. The switch 10 is provided with a common contact 16 connected by means of wire 17 to the primary 18 of an induction coil. A wire 19 leads from the other terminal of the primary to the ground through a condenser 20. The same terminal of an induction coil is also connected to the common contact 21

of a switch 22 by means of wire 23. Switch 22 is adapted to make contact either with contact 24 or contact 25.

26 represents a double interrupter comprising two independent interrupters, the interrupting action of which produces a spark in the sparking devices, which interrupters are composed of bell crank levers 27 and 28 fulcrumed at 29 and 30 respectively, carrying contacts 31 and 32 respectively, adapted to make contact with contacts 33 and 34, respectively. Springs 35 and 36 normally maintain the contacts 31 and 33 and 32 and 34, respectively, closed.

37 and 38 represent stationary guides having surfaces along which rollers 39 and 40 are adapted to move respectively, the rollers being loosely mounted on pins 41 and 42, respectively. Arranged on the constantly rotating shaft 43 is a cam 44 having two cam faces 45 and 46, both of which are adapted to engage both of the rollers 39 and 40 and cause them to move along the guides 37 and 38 to engage the ends 47 and 48 of the levers 27 and 28 respectively, to cause the levers to rotate about their pivots and the contacts 31 and 33 and 32 and 34 to be separated, respectively.

The contacts 31 and 32 are connected to ground by means of wires 49. The contact 33 is connected to the contact 24 by means of wire 50. Contact 34 is connected to contact 25 by means of wire 51.

As shown in the drawing, the system is supplied by a direct current from the battery 6, the primary circuit being as follows: From the one side of the battery through wire 11, contact 9, switch 10, contact 16, wire 17, primary 18 of the induction coil, wire 23, contact 21, switch 22, contact 24, wire 50, contacts 33 and 31 of the interrupter, wires 49, to ground. The secondary circuit may be traced from the ground at 52 through the secondary 53 of the induction coil, wire 5, distributor arm 4, distributor contact 3 to the sparking device 1, thence to ground.

Now, in case it is desired to operate the system from the alternating current source 12 the switches 10 and 22 are thrown to make contact with contacts 15 and 25 respectively. The secondary circuit supplying the spark plugs remains as before while the

primary circuit is as follows: From the source 12, wire 14, contact 15, switch 10, contact 16, wire 17, primary 18 of the induction coil, wire 23, contact 21, switch 22, contact 25, wire 51, contacts 34 and 32 of the interrupter and wires 49 to ground.

It will further be noted that if one set of contacts becomes bad or should fail for any reason, the switch 22 may be thrown to connect the other set of contacts in circuit irrespective of whether the switch 10 is thrown or not, that is, irrespective of whether the battery or alternating current source is supplying the system. It will further be noted that a single cam member 42 operates both of the independent interrupters so that the interrupter is compact and more simple, and occupies a much smaller space than would be the case if separate cams on the shaft operating separate interrupters, were used.

Although I have described my improvements in great detail and with respect to one particular embodiment thereof, nevertheless I do not desire to be limited to such details, as many changes and modifications may well be made without departing from the spirit and scope of my invention in its broader aspects.

Having fully and clearly described my improvements, what I claim as new and desire to secure by Letters Patent, is:

1. An ignition system for gas engines and the like, comprising in combination, an alternating current circuit and a direct current circuit, an induction coil, a distributor and sparking devices in operative relation with one another, means for connecting the sparking devices in either of said circuits, two interrupters, the interrupting action of which produces a spark in the sparking devices, switching means whereby one of said interrupters is thrown into circuit, the other interrupter may be thrown out of circuit, and a cam operating both of said interrupters.

2. An ignition system having in combination, sparking devices, an alternating current circuit and a direct current circuit, either of which is adapted to supply the sparking devices, two interrupters the interrupting action of which produces a spark at the spark-

ing devices, one in each circuit, and a cam operating both interrupters.

3. The combination of a direct current circuit and an alternating current circuit, two independent interrupters the interrupting action of which produces a spark at the sparking devices, one in the direct current circuit and one in the alternating current circuit, and a single cam operating both interrupters.

4. An ignition system having in combination, an induction coil, a distributor and sparking devices operatively connected, two independent interrupters the interrupting action of which produces a spark at the sparking devices, means for connecting either interrupter in circuit with the induction coil, at will; and a single cam operating both interrupters.

5. An ignition system having in combination, sparking devices, two independent interrupters the interrupting action of which produces a spark at the sparking devices, means for connecting either interrupter in circuit to feed the sparking devices at will, and a single cam operating both interrupters.

6. An ignition system for gas engines and the like, comprising in combination, an alternating current circuit and a direct current circuit, an induction coil, a distributor and sparking devices in operative relation with one another, means for connecting the sparking devices in operative relation with either of said circuits, two interrupters; means for connecting either interrupter in either circuit, and a cam operating both of said interrupters.

7. An ignition system having in combination, sparking devices, an alternating current circuit and a direct current circuit, either of which is adapted to supply the sparking devices, two interrupters, and means for connecting either interrupter in either circuit.

In testimony whereof, I have signed my name to this specification, in the presence of two subscribing witnesses.

CARL HARTMANN.
